UNITED STATES PATENT OFFICE.

JOHN A. TAFT, OF CINCINNATI, OHIO.

COTTON CONDENSER.

Application filed February 9, 1926. Serial No. 87,161.

My invention relates broadly to cotton condensers and particularly to novel means for regulating the uniformity of thickness of the bat formed in the condenser.

In the art the use of condensers for collecting cotton lint and forming it into a bat is quite extensive. From the cotton gin stands the cotton lint is usually blown with air into an enclosed chamber in which means are provided for separating the cotton lint from the carrying air, and in which means are also provided for forming the separated lint into a bat. Due to the variableness of the air currents in the conduit from the gin stands to the condenser caused by increasing and decreasing the number of gin stands in operation, it is always a problem to regulate the flow of air and lint so that a bat of even thickness may be formed.

Condensers have been designed with means adapted to regulate the thickness of the bat by controlling the volume of air currents carrying the lint to different parts of the condenser. As an example of a system in which the control of the thickness of the bat is by means of air volume adjustment devices, reference is made to my Patent Number 1,379,229. In this patent arrangement is made for a divided receiving drum in which each half of the drum has an independent air discharge passage. The provision of dampers in this air passage provides means of adjusting the volume of the air currents to each half of the receiving drum so that when one half of the web of the bat is thicker than the other half, it is a simple matter to regulate the dampers to discharge more lint onto the bat forming rolls on the thin side of the web. While such air current broadly controls the thickness of the web of batting I have found that it does not provide an adjustment having sufficient positive action to permit nice regulation of the uniformity of the thickness of the web.

It is the object of my invention to provide diverting boards within the condenser which will divert the direction of flow of the lint stream subsequent to its discharge from the air drum and which will in this way provide a means of regulating the forming of the web on the bat forming rolls, which will enable much more accurate control of the uniform thickness of the web.

Referring to the drawings in which I have illustrated a preferred type of condenser in

combination with which I have further shown my preferred types of diverters:

Figure 1 is a front elevation of a condenser having two sets of diverters.

Figure 2 is a side elevation of the condenser shown in Figure 1.

Generally indicated at 1 is the lint flue through which air currents carry the cotton lint into the casing 2 of the condenser, the flow of cotton being from the broken away portion of the flue 1 upwardly into the casing 2 as indicated in Figure 1. Within the casing the air drum 3 is shown which has a perforated outer periphery 4 through which the air is drawn or forced. The air passes out through the open ends of the air drum and up through the conduits 5 to the stack. The cotton lint which is centrifugally thrown from the outer periphery of the air drum which rotates at a rapid speed, passes down through the casing and is deposited on the bat forming rolls 6. These bat forming rolls also have perforated peripheries through which air passes into the lower portions of the air conduits 5. The bat formed on the forming rolls then passes to the lower squeeze rolls 7 from which a solid web of cotton is usually discharged into a baling press.

For controlling the uniformity of the thickness of the web of cotton batting I have provided an upper set of diverting blades 8 which are preferably journaled in the casing and which are provided with handles 9 with which the direction of the blades may be changed. The handles are also preferably cooperatively linked together as indicated at 10 so that a single movement of the handle will vary the direction of the set of blades and thereby divert the direction of flow of the lint stream being projected from the air drum. Secured to a vertical wall of the casing I also mount another set of diverting blades 11 which provide a lint flow control which may be used in conjunction with the control blades 8. These blades 11 are preferably connected by a link so that their direction may be changed by a single movement of a handle 12.

While I have shown two sets of diverting blades, each set being composed of two blades, a greater number may be used effectively. I have found that one blade does not control the direction of flow of the lint stream as well as two blades connected by a link so that both operate together. It is,

therefore, my purpose to claim broadly a positive means of diverting the direction of flow of the lint stream with more specific claims to the particular arrangement herein disclosed.

Having thus described my invention, what I claim as new and desire to secure by Letters Patent, is:—

In a cotton condenser having a lint flue connected therewith, an air drum, and bat forming rolls therein, said condenser having a passage between said drum and said rolls, diverting means disposed in said passage for

diverting the direction of flow of the lint stream, said diverting means comprising at least one set composed of a plurality of blades disposed in the direction of flow of the lint stream in said passage, and said set of blades having controlling members adjustable from the outer side of the condenser, said controlling members provided with co-operating connections whereby adjustment of one blade will correspondingly move another blade in said set.

JOHN A. TAFT.
